UNITED STATES PATENT OFFICE.

OTTILIE REBSAMEN, OF ZURICH, SWITZERLAND, ASSIGNOR TO THE FIRM REBSAMEN & CO., OF ZURICH, SWITZERLAND.

CORSET.

Application filed December 13, 1921. Serial No. 522,051.

To all whom it may concern:

Be it known that I, OTTILIE REBSAMEN, citizen of the Republic of Switzerland, residing at Falkenstrasse 4, Zurich, Switzerland, have invented certain new and useful Improvements in Corsets, of which the following is a specification, reference being had therein to the accompanying drawing.

The invention relates to improvements in corsets having straps passing below the arms and a biparted breast-portion. According to the invention the length of each of said straps is singly adjustable for the purpose of modifying the shape of the corset. The back portion and the breast portion may be connected together by means of exchangeable intermediate members such as straps, which are provided at least at one end with eyelets, by means of which they are fastened to the breast portion and to the back portion respectively of the corset through the intermediary of flexible stays pushed through the eyelets.

Constructional examples of the corset according to the invention are illustrated on the accompanying drawings in which:

Fig. 1 is a view of a first constructional example,

Figs. 2 and 3 illustrate details of Fig. 1 on a larger scale,

Fig. 4 illustrates in a perspective view a second constructional form,

Fig. 5 is view of a third constructional form and

Figs. 6-11 illustrate details of the latter on an enlarged scale.

Referring now to the constructional form illustrated in Figs. 1-3, 1 and 2 denote the halves of the breast portion. Each half 1 and 2 of the breast portion comprises a curved center part made of fabric which is framed by means of four straight tapes 1^a, 1^b, 1^c, 1^d and 2^a, 2^b, 2^c, 2^d respectively. 3 and 4 are the halves of the back portion and 5 and 6 are the halves of the body portion of the corset. The parts 1 and 2 of the breast portion are connected to the back portions 3 and 4 by means of straps 7, for instance by elastic straps, passing under the arms of the wearer. These straps 7 pass through loops of a tape 8 adapted to

distance said straps and which are slidably arranged along the straps. The straps 7 are connected with their one ends by means of eyelets taking over buttons 9 provided on the body portion. The other ends of the straps 7 are formed into loops 11 by means of slip buckles 10 and pass through loops provided on the tapes 12 sewn to the framing tapes 1^b and 2^b. In this manner 60 the length of each strap 7 can be varied whereby the shape of the corset can be modified. The straps may also be secured to the breast portion by means of loops and buttons whilst maintaining the possibility of varying their lengths. To the breast portions 1 and 2 shoulder straps 13 are secured, their other ends being connected to buttons on the back portion by means of loops and ribbons 14 the length of the 70 latter being adjustable. Both ends of the shoulder straps 13 may be detachably connected to the respective portions of the corset. Further straps, the length of which can be varied by means of slip buckles 10, 75 are provided in the lower part of the breast portions 1 and 2, which straps are detachably connected by loops to buttons 15 of the body portion; their upper ends may be secured in a similar manner. In this constructional example the body portions 5, 6 have the shape of a body former and are provided with stiffeners 16 which are also arranged in the back portion and which hold the latter stretched. The stiffeners 16 85 (Fig. 3) are concealed in casings 17 formed between the fabric and casing cover strip 18 which strip has a portion between its ends that is not sewn to the fabric at its lateral edges, so that the stiffeners 16 can 90 be removed when the corset has to be washed. The cover-strips 18 possess the further advantage that the stiffeners 16 do not pinch when the corset is worn directly on the body. For the same reason a flap 85 19 is provided which is secured by the lacing 20 to the body portion and which is buttoned up by loops 21 to buttons 22 of the body portion. The slideable tapes 8 may be provided with removable stiffeners in 100 the manner shown with the stiffeners 16. The advantages of the constructional

example hereinbefore described are first of all the feature that the shape of the corset can be modified by varying the length of the straps 7, whereby the tapes 1^a—1^d and 5 2^a—2^d framing the breast portion prevent a deformation of the latter. Furthermore the breast portion 1, 2 may be detached from the back portions 3, 4 and from the body portion 5, 6 so that it can be exchanged 10 for richly or less richly embroidered parts of fabrics according to the dress with which the corset is worn, and it can also be washed separately. Further all the straps can be detached and the stiffeners removed and 15 thus all portions of the corset, breast portion, back portion and body portion, can be boiled and washed.

In the constructional example illustrated in Fig. 4 the shoulder straps 13 are omitted. 20 This is rendered possible because the back portion is stiffened in the manner shown in Fig. 1, and because the straps 7 the length of which can be adjusted to permit of a good fit of the breast parts 1 and 2 to the body. 25 Instead of the body portion 5 in the shape of a body former as shown in Fig. 1 a waist belt 5^a is provided.

The constructional example shown in Fig. 1 may also be used without the shoulder 30 straps 13. Obviously the straps 7 the length of which can be varied could extend from the lateral end of the one half of the breast portion to the lateral end of the other half of the breast portion so that they form at 35 the same time the back portion of the corset; some stiffened slidable tapes 8 have to be arranged in this portion.

In the constructional example illustrated in Figs. 5-11 the upper part of the corset 40 shows the bipartite back-portion 31 and the bipartite breast portion 32. Both portions are interconnected by intermediate members 33 in the shape of straps. 34 denotes the bipartite lower or body portion of the corset. 45 In this portion casings 35 formed by the fabric, which casings are open in their upper part and closed at the bottom, are provided. In the casings adjacent to the lacing 36 of 50 the lower corset portion 34 broad flexible stays 37 are loosely inserted which are supported at their lower end in the fabric casings 35. The projecting upper parts of these broad stays 37 extend into fabric casings 38 provided in the back portion 31 and connect 55 the later in this manner with the lower portion of the corset and support it. The inner walls of the casings 38 are provided in their upper part with a number of transverse slots 39 so that the upper parts of the broad 60 stays 37 may be inserted at different heights into the casings 38. (Figs. 8 and 9.) Other casings 40 in the fabric of the lower portion contain removable stays or stiffeners 41 which only extend up to the upper edge of 65 the lower portion of the corset.

The connection between the back portion 31 and the lower portion 34 as well as between the breast portion 32 and the lower portion 34 is further effected by smaller flexible stays 42 in addition to the main 70 stays 37. In their upper parts the stays 42 project into casings 44 which are provided on the tapes extending in an upward direction in the lateral sides adjacent to each other of the breast and back portions, which 75 tapes are connected to each other by the intermediate members 33. The stays 42 of the casings 44 that are provided at the back portion project into casings 43 of the lower portion situated close by the broad stays 41. 80 The inner walls of the casings 44 are provided with transverse slots 46 arranged at regular intervals. It is thereby rendered possible to insert the upper parts of the stays 42 so into the casings 44 that they 85 bridge over a part 45 situated between two transverse slots 46. At these spots the stays 44 pass through the eyelets 47 of the intermediate members 33, which can be done in two ways as is shown at *a* and *b* in Figs. 6 90 and 7. In this manner an easily detachable connection having no buttons for the intermediate members at different heights on the breast portion and the back portion is attained. In order to prevent a longitudinal 95 displacement of the stays 42 and the upper portion of the corset the stays 42 (Fig. 11) are provided in their upper portion with a notch 48 with which a loop 47 is in engagement (Fig. 6) thus preventing said longitudinal 100 displacement of the stay 42.

I claim:

1. In a corset, a body portion having a laced stay portion at the back extending above the waist, a detachable and exchangeable, bi-partite breast portion, independently adjustable straps for passing under the arms connecting the breast portion to the body portion, means to permit said straps to be connected at different vertical positions and means to individually adjust the length of the straps.

105

2. In a corset, a body portion, a removable, laced back portion detachably connected to the body portion and above the same, means to adjust the height of said back portion with respect to the body portion, a removable, bi-partite breast portion exchangeable for different dresses, removable straps between said back portion and breast 110 portion, means to individually adjust the length of said straps, and means between the breast portion and body portion to vertically adjust the height of the breast portion with respect to the body portion.

115

3. In a corset, a body portion, a removable, laced back portion, detachable stays stiffening said back portion and extending into the body portion and stiffening the latter, means in said back portion to adjust its 120

125

130

height relatively to said stays, a removable, bi-partite breast portion having a stay at the rear portion of each part, extending into said body portion and removable therefrom, means to permit the vertical adjustment of the breast portion with respect to the latter stays, and straps connecting the breast and body portions, said straps adjustable along the opposing edges of the breast and body portions. ¹⁰

In testimony whereof I affix my signature.

OTTILIE REBSAMEN.
